UNITED STATES PATENT OFFICE.

HIRAM H. GIFFORD AND WILLIAM GIFFORD, OF TRAVERSE CITY, MICHIGAN.

MAGNETIC CHOKING DEVICE.

1,231,875.

Specification of Letters Patent.

Patented July 3, 1917.

Application filed June 10, 1916. Serial No. 102,989.

To all whom it may concern:

Be it known that we, HIRAM H. GIFFORD and WILLIAM GIFFORD, citizens of the United States, residing at Traverse City, in the 5 county of Grand Traverse, State of Michigan, have invented a new and useful Magnetic Choking Device, of which the following is a specification.

The present invention appertains to choking devices such as are used in electrical conductors, and aims to provide a novel and improved yet simple and inexpensive magnetic choking device for use in electric service and transmission lines in conjunction 15 with ordinary lightning arresters for the protection of a transformer or other electrical equipment against damage by lightning.

It is the object of the invention to provide 20 a magnetic choking device which will arrest or retard the instantaneous rush or surge of electrical current past the choking device to the electrical apparatus, as when the conductor is charged by a stroke of lightning or other high frequency electrical disturbance of similar nature, whereby to protect the electrical apparatus and to give the lightning arrester sufficient opportunity to act before the high frequency current can 25 pass the choking device.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without 40 departing from the spirit of the invention.

The invention is illustrated in the accompanying drawing, wherein:—

Figure 1 is a longitudinal section of one 45 form of the choking device, portions being shown in elevation.

Fig. 2 is a similar view of another form.

Fig. 3 is an elevation of a third form of the invention, portions being broken away and shown in section.

Fig. 4 is a view similar to Fig. 3 of another variation.

Fig. 5 is an end view of the device shown in Fig. 4.

The magnetic choking device shown in 55 Fig. 1 comprises a thick-walled tubular body 1 of iron or steel and provided with a

longitudinal bore or recess 2 extending from one end to a point adjacent the other end, there being a reduced aperture 3 extending from the last mentioned end of the body to the bore 2. Threadedly or otherwise engaged within the aperture 3 is a bushing 4 of insulating material, which is provided with a convexed hood 5 for shedding rain and moisture to the sides of the body, the present device being adapted especially for use in a vertical position with the bushing 4 at the upper end of the body. Another bushing or plug 6 of insulating material is threadedly or otherwise engaged within the lower end of the bore 2, and has an enlargement 7 resting against the lower end of the body 1. As a convenient means for supporting the body 1, one side thereof can be formed or provided with an outstanding screw 8 to be threaded into the cross arm of the pole which supports the conductors, although the body 1 can be supported in any suitable manner. The bushings 4 and 6 are apertured for the passage of the conductor 9 therethrough, and said conductor has a coil or helix 10 within the bore 2 between the bushing or plug 6 and the shouldered end of the bore 2, said conductor being insulated to insulate it from the body 1.

In practice, the choking device is interposed in the conductor between the lightning arrester and electrical equipment (not shown) to be protected, and should the conductor 9 be struck by lightning or otherwise subjected to a high frequency electrical disturbance of similar nature, the choking device will retard or check the flow of current to the electrical apparatus, thus protecting it from injury in connection with the lightning arrester. The lightning arrester is thus given an opportunity to act in order to prevent the abnormally high voltage current from passing to the electrical equipment. An ordinary current will flow along the conductor past the body 1 without difficulty where the number of turns of the helix are of proper ratio to the amount of current flowing through the conductor, but with lightning or similar electrical disturbance, the conditions are reversed. Lightning or equivalent high frequency electrical current will leave a complete metallic path of low ohmic resistance and jump an air gap that a normal line current would not, rather than pass the magnetic choking device. This is due to the

high self induction set up in the magnetic choke device by currents of a highly oscillatory character, such as produced by lightning. The conductor in extending past the iron or steel body 1 provides the choking effect due to the fact that a high frequency current will set up magnetic fields in the body 1 which resist the flow of the high frequency current.

19 The device can be used wherever necessary, and while applicable to indoor installations, is especially adapted for out door service, to protect out door transformer installations, meters, etc. The surface of the 5 body 1 and insulating bushings can be coated by enamel or other material whereby to protect the device from the elements. The device can be constructed in different sizes and proportions for currents of different voltage, and is adapted to supersede the more expensive and less efficient choke coils now in use for the service that the present choke device is designed. The present device is thoroughly efficacious in use, is easily 15 installed, is non-destructible, and is cheaper and superior in many respects over choke coils which are commonly used. The body 1 is of such formation and is associated with the conductor in such a way that in the 20 presence of a high frequency current, the magnetic field is set up in the body proportionate to the flow of current, and this consumes a sufficient period of time during which the potential builds up, between the 25 magnetic choke device and conductor to a point sufficiently high, to cause the lightning arrester to discharge and carry the current to ground. In so doing, the apparatus protected is relieved from the great strain 30 it would otherwise be subjected to, and the danger of a break down is greatly lessened. The body 1 also protects the helix 10. The interior as well as the exterior of the device can be coated by enamel, or the like, to insulate and render the device weather proof. 35

The device shown in Fig. 2 is of slightly different formation than that shown in Fig. 1. This second form of the device is of the "hour glass" type, the iron or steel body 1^a having the "hour glass" bore 2^a which is of a constricted diameter between its ends and which increases in diameter toward the ends of the body 1^a. This device, the same as that shown in Fig. 1, is adapted for use in 50 a vertical position, although it can be used in a horizontal or other position. A bushing 4^a of insulating material is threaded or otherwise engaged within the upper end of the body 1^a and is provided with a convexed 55 portion 5^a for shedding rain, and the like. A bushing or plug 6^a of insulating material is threadedly or otherwise engaged within the lower end of the body 1^a and has an enlarged portion 7^a bearing against the 60 lower end of the body. The bushings 4^a and 65

6^a are apertured for the passage of the conductor 9^a, which is provided with a "hour glass" type of coil 10^a fitting snugly within the bore 2^a. The exterior of the body 1^a is also preferably shaped as seen in Fig. 2, in preference to the shape of the body 1. The body and bushings can be enameled externally and interiorly to protect them from the elements, and due to the use of the "hour glass" coil 10^a, the device is particularly efficient for its intended purpose. 70 75

The device shown in Fig. 3 has an external instead of an internal coil as used in the devices shown in Figs. 1 and 2.

The device in Fig. 3 has a body 1^b of ovoid form, and provided with a longitudinal bore 2^b extending therethrough and through which a bushing 4^b of insulating material extends, said bushing being tubular for the reception of the conductor 9^b. The body 1^b is provided with a helical groove 11^b in its periphery or circumference, the axis of said groove being coincident with the axis of the body, and the body has radial bores 12^b extending from the ends of the groove 11^b to the bushing 4^b through which the conductor 9^b extends, and said conductor has a coil or helix 10^b seated within the groove 11^b. The groove 11^b is preferably filled with insulating cement or equivalent material 13^b, and the surface of the body and bushing are preferably enameled or similarly finished. 80 85 90 95

Figs. 4 and 5 illustrate a "squirrel cage" type of choking device, embodying the body 1^c of iron or steel, and provided with a longitudinal bore 2^c through which the insulated bushings 4^c extends, the conductor 9^c extending straight through the bushings 4^c. The body 1^c is provided upon its exterior 100 with longitudinal grooves 11^c and with annular grooves 11^d at the ends of the grooves 11^c, and longitudinal strips 10^c are seated within the grooves 11^c and have their ends secured to rings 10^d lying within the grooves 11^d, to provide the squirrel cage. The grooves 11^c and 11^d are filled with insulating cement 13^c and the device is coated with enamel or equivalent material to protect the same from the elements. It has been found 110 115 that a high frequency current passes with great difficulty through this type of magnetic choking device.

The enamel and cement used provide for the insulation of the device as well as protecting it from the elements. 120

Having thus described the invention, what is claimed as new is:

1. A magnetic choking device embodying a thick-walled tubular body of magnetic material, insulation therein projecting from its ends, a conductor extending into and out of said body through said projecting portions of the insulator and provided therebetween with a coil inclosed by the body, to pro- 125 130

vide a choking effect to a high frequency current.

2. A magnetic choking device embodying a thick-walled tubular body of magnetic material having a helical groove in its periphery, insulating material within said body projecting from the ends thereof, and a conductor extending into and out of the ends of the body through the projecting portions 10 of the insulating material and having a coil

therebetween seated in said groove and inclosed by the body.

In testimony that we claim the foregoing as our own, we have hereto affixed our signatures in the presence of two witnesses.

HIRAM H. GIFFORD.
WILLIAM GIFFORD.
